CIGARETTE

Rowland Frank May, Potters Bar, England, assignor to Filter Tips Limited, London, England

Application February 1, 1937, Serial No. 123,515
In Great Britain January 24, 1936

13 Claims. (Cl. 131—39)

This invention relates to cigarettes and is particularly concerned with an improved method and apparatus for the production of filter tip and like composite cigarettes by uniting axially aligned cigarettes or lengths of cigarette rod and filter tips or mouthpiece portions by means of uniting bands or wrappers.

The invention has for its primary object to provide an improved method of and means for applying the uniting bands or wrappers around the assembled lengths whereby the uniting operation may be effected without any rolling or other movement of the cigarettes, and whereby the wrapping pressure may be maintained to ensure proper adhesion while the assemblages are being fed axially.

The present invention furthermore renders it possible, in a method involving the wrapping of uniting bands around assembled lengths fed axially to and from wrapping means, to effect the initial application of the uniting bands to the assemblages while the same are stationary and positioned in registration with the means for applying the uniting bands or wrappers.

According to the present invention, the lengths to be united, assembled in line and after uniting bands or wrappers have been brought into contact therewith, are fed axially and intermittently, and the wrapping of the uniting bands or wrappers around the lengths to be united is effected by the action of means moving lengthwise of the assemblage in a direction opposite to the feed movement thereof, the wrapping operation taking place during a period or periods when the assemblage is stationary. The wrapping operation is effected by means reciprocated in the lengthwise direction of the assemblage, the wrapping movement in a direction opposite to the direction of feed taking place when the assemblage is stationary and the return movement coinciding more or less with the forward movement of the assemblage.

Owing to the fact that during the forward movement of the assemblage the wrapping device moves substantially therewith, the wrapping pressure on each uniting band is maintained throughout the feed movement with the result that effective adhesion is ensured.

The invention is hereinafter described by way of example with reference to the accompanying diagrammatic drawings, in which:—

Figures 1 and 1a taken together show a side elevation partly in section illustrating one embodiment of apparatus adapted for carrying out the invention;

Figure 2 is a section taken on line II—II of Figure 1;

Figures 3 and 4 are sections on the lines III—III and IV—IV respectively of Figure 1a; and

Figure 5 is a sectional view taken on line V—V of Figure 1.

In carrying the invention into effect according to one embodiment, pairs of cigarettes 1, 1a and interposed double length filter tips 2 or mouthpiece portions are fed respectively from hoppers 3, 3a and 4 into grooves in a drum 5 which is moved intermittently, for instance by means of a helical cam 7a engaging a gear 5a on the drum spindle and mounted on a shaft 7b driven through bevel gears 7c, 6a from the main shaft 6. Each assemblage comprising two cigarettes 1, 1a and an interposed double length filter tip 2, is discharged in turn on to a belt 9 carried on rollers 9a and by which the assemblage is moved axially. Preferably the belt 9 moves continuously and the lengths constituting the assemblage are simultaneously deposited on the belt 9 by means of fingers 8 carried by levers 8a pivoted on brackets 14a projecting from the bed 14 of the machine and operated, for instance, by eccentrics 6b the straps 8b of which are connected to the lower end of the levers 8a. Cams 6c on the shaft 6 co-operate with levers 8c which through links 8d raise the fingers 8, the downward movement thereof being effected by springs 8e (Figure 3). In operation the fingers 8 are projected into circumferential slots 5b in the drum 5 so as to lie above the leading assemblage and as the fingers 8 again move outwardly they are caused to drop so as to engage the assemblage and roll the same on to the belt 9.

The assemblage deposited on the belt 9 is positioned by means of a guide 9b and is conveyed axially by the belt 9 into an inverted C-shaped guide 9c and up to a stop 10. The stop 10 is pivoted at 10a and is operated by means of a cam 10d mounted on a shaft 10e driven through bevel gears 10f, 6d from the main shaft 6. The cam 10d operates the stop 10 through a push rod 10b provided with a return spring 10c. By means of the stop 10 the assemblage is positioned in the inverted C-shaped guide 9c with its lower part exposed and in correct registration with means for applying a uniting band 11.

As shown in Fig. 4, the uniting bands 11 are fed into position on an intermittently moving belt 12 having perforations 12a and passing over a suction box 13 having suction holes 13a and a flexible suction pipe 13b. The suction box 13 is pivoted about the axis of a roller 13c on a spindle 55

13d and is adapted to be raised and lowered by means of a cam 6e on the main shaft 6 operating on a lever 16 connected, by means of a link 16a, to the spindle 13g of a roller 13e around which 5 the perforated belt 12 passes, a return spring 16b being provided. The belt 12 is led on to the suction box 13 over a stationary suction box 15. Thus, after an assemblage is positioned as shown 10 in Figure 1, the operation of the cam 6e raises the suction box 13 and thus presses the leading uniting band 11 into contact with the assemblage. The cam 6e is arranged to maintain the suction box 13 in the raised position while the stop 10 is released and the assemblage is discharged axially 15 by the feed movement of the next following assemblage on the belt 9 and in order to maintain the uniting band 11 in contact with the assemblage during this movement, the suction box 13 may be provided with an extension plate 13f 20 as shown in Figure 1.

The axially moving assemblage with the uniting band attached is engaged by rollers 17, 17a, the lower roller 17a being cylindrical and the upper roller 17 being grooved and preferably being driven, for instance, through gears 17b, 18g so as to have a slight accelerating action on the assemblage which is thereby delivered through 25 an extension 9d of the inverted C-shaped guide on to a conveyor belt 18. The conveyor belt 30 18 passes around rollers 18a, 18b, 18c, a large diameter driving roller 18d and a guide roller 18e, the usual tensioning roller 18f being provided. The driving roller 18d is driven intermittently by the engagement of a gear segment 19 35 with a gear 18h on the drum spindle, the driving roller 18d being positively held during periods of non-rotation by the co-operation of a stop disc 18i with a corresponding part on or attached to the gear segment 19. The gear segment is 40 mounted on a shaft 19a driven from the shaft 6 through helical gears 19b, 6f. The diameter of the driving roller 18d preferably is such that each movement which, as shown in the drawings, may correspond to a quarter of a revolution of the 45 roller, is equal to the length of one assemblage.

A wrapping device 20 reciprocable lengthwise in relation to the assemblage is provided and such wrapping device 20 conveniently is in the form of a travelling garniture slidable along 50 guides 14b and co-operating with the belt 18. The device 20 may be driven from a crank disc 21 on the shaft 10e before referred to through a link 21a, lever 21b and link 21c. The drive to the roller 18d and to the wrapping device 20 55 is timed so that during the forward movement of the belt 18 the device 20 moves substantially therewith and so that backward movement of the device 20, during which the wrapping of the uniting bands is effected, takes place during periods when the belt 18 is stationary. Preferably, 60 as in the arrangement shown, the device 20 effects the wrapping of each uniting band around the respective assemblage in two stages and after each stage the wrapping pressure is maintained 65 during the period of forward movement of the belt 18 and the device 20.

On the completion of the wrapping movement of the device 20 the foremost assemblage, with the uniting band completely wrapped therewith, is left free on the belt 18 and on the next forward movement of the belt 18 the assemblage 70 is moved into engagement with accelerating rollers 22, 22a which may be driven through gears 22b, 18j and whereby the united assemblage is delivered into a flute in a drum 23 and up to a 75

stop plate 24. By the drum 23 the assemblages are carried past a rotary cutter 26 by which the assemblages are bisected to produce individual cigarettes. During the cutting operation the assemblages are positioned between the stop plate 5 24 and a corresponding side plate 24a and are maintained in the grooves in the drum 23 by means of curved guides 28. The drum 23 may be driven intermittently by means of a helical cam 25 mounted on a shaft 25a driven through 10 gears 25b, 6g from the main shaft 6.

The cigarettes are finally discharged down inclined guides 27 on to conveying means such as a belt 29 passing over a roller 29a.

In Figure 1 the driving roller 18d is shown as 15 having just completed a quarter of a revolution and the wrapping device 20 is about to move in the direction opposite to the direction of feed. It will be seen that during this movement of the device 20 the uniting band 11a, which had been 20 partially wrapped around the assemblage during the previous wrapping movement, will be completed, while the uniting band 11 applied to the succeeding assemblage will be partially wrapped therearound, but at the same time the leading 25 assemblage on the belt 18 around which the respective uniting band 11 will be completely wrapped will be left free on the belt for discharge by the rollers 22, 22a on the next forward 30 movement of the belt 18. In the position shown in Figure 1 also an assemblage has just been accelerated into a flute in the drum 23 by the operation of the rollers 22, 22a and the stop 10 has just moved to the engaging position to arrest the movement of an assemblage previously delivered on to the belt 9 by the operation of the fingers 8. The belt 12 carrying the uniting band has just moved to bring the band 11 into position, and the suction box 13 is about to be raised to apply the band to the assemblage. During 40 the movement of the wrapping device the drums 5 and 23 are moved so that on the next forward movement of the belt 18 the drum 23 presents an open flute for the reception of the leading united assemblage while the drum 5 brings an assemblage into position for transfer on to the belt 9 after the stop 10 has been released.

Although the wrapping device 20 preferably moves substantially with the belt 18 on its forward stroke, a certain amount of relative movement between the wrapping device 20 and the belt 18 is permissible and would have no effect on the operation.

Furthermore, it will be understood that the invention is applicable to the production of composite cigarettes containing two different kinds of tobacco and is also applicable to the production of cigarettes in which a tubular reinforcement or filter wad is provided at an intermediate position in its length.

I claim:

1. Apparatus for the production of composite cigarettes, comprising an endless conveyor by which assembled lengths of cigarette rod and filter tips to be united, with uniting bands attached thereto, are fed axially, means for driving the conveyor intermittently, wrapping means reciprocable lengthwise of the conveyor, and mechanism operating the said wrapping means so that its wrapping movement in a direction opposite to the feed movement of the conveyor takes place while the conveyor is stationary and so that its return movement coincides substantially with the forward movement of the conveyor.

2. Apparatus as claimed in claim 1, wherein the endless conveyor constitutes a wrapping belt, and wherein the wrapping means is in the form of a travelling garniture co-operating with the belt.
- 5 3. Apparatus for the production of composite cigarettes, comprising means for assembling lengths of cigarette rod and mouthpiece portions in alignment to form assemblages, means for applying a uniting band to the assemblages, conveying means for conveying the assemblages successively and axially to said means for applying a uniting band thereto, means for registering an assemblage axially in relation to the uniting band-applying means, an endless conveyor belt, means for feeding an assemblage, with a uniting band attached thereto, on to the endless conveyor belt, an axially reciprocable wrapping device associated with said conveyor belt, means for reciprocating said wrapping device and for driving the conveyor belt intermittently so that the periods of rest of the belt coincide with rearward movement of the wrapping device and so that the forward movements of the belt coincide substantially with the forward movements of the wrapping device, cutting means for bisecting the assemblages to produce individual cigarettes, and means for conveying the assemblages to said cutting means.
- 10 30 4. A method for the production of composite cigarettes by uniting axially aligned lengths of cigarette rod and mouthpiece portions by means of uniting bands, comprising assembling the lengths to be united in axial alignment to form an assemblage, bringing a uniting band in contact therewith, feeding the assemblage with said uniting band in contact therewith axially and intermittently, and displacing a wrapping device lengthwise of said assemblage in a direction opposite to the direction of travel of the assemblage, between intermittent feed movements of said assemblage and while the latter is stationary, to effect wrapping of the uniting band about said assemblage.
- 15 40 45 50 55 60 65 70 75 80 85 90 95 100 105 110 115 120 125 130 135 140 145 150 155 160 165 170 175 180 185 190 195 200 205 210 215 220 225 230 235 240 245 250 255 260 265 270 275 280 285 290 295 300 305 310 315 320 325 330 335 340 345 350 355 360 365 370 375 380 385 390 395 400 405 410 415 420 425 430 435 440 445 450 455 460 465 470 475 480 485 490 495 500 505 510 515 520 525 530 535 540 545 550 555 560 565 570 575 580 585 590 595 600 605 610 615 620 625 630 635 640 645 650 655 660 665 670 675 680 685 690 695 700 705 710 715 720 725 730 735 740 745 750 755 760 765 770 775 780 785 790 795 800 805 810 815 820 825 830 835 840 845 850 855 860 865 870 875 880 885 890 895 900 905 910 915 920 925 930 935 940 945 950
- effect a first stage of wrapping of the uniting band about said assemblage, displacing said wrapping device, while in engagement with said assemblage and before completion of the wrapping operation, in the opposite direction substantially coincidentally with the intermittent feeding movement of the assemblage, and again displacing said wrapping device in the direction opposite to the direction of feed of the assemblage between intermittent feed movements and while said assemblage is stationary to complete the wrapping of said uniting band or wrapper about said assemblage.
- 5 7. A method for the production of composite cigarettes by uniting axially aligned lengths of cigarette rod and mouthpiece portions by means of uniting bands, comprising assembling pairs of single cigarettes with double-length mouthpiece portions interposed between them to form an assemblage, feeding the assemblage axially and intermittently, applying a uniting band to the assemblage while stationary, further feeding the assemblage with said uniting band in contact therewith axially and intermittently, and displacing a wrapping device lengthwise of said assemblage in a direction opposite to the direction of travel of the assemblage, between intermittent feed movements of said assemblage and while the latter is stationary, to effect wrapping of the uniting band about said assemblage.
- 10 8. A method for the production of composite cigarettes consisting in assembling lengths of cigarette rod and mouthpiece portions in axial alignment to form an assemblage, feeding each assemblage axially, stopping the feeding movement of the assemblage, applying a uniting band to said assemblage while stationary, displacing the assemblage, with the uniting band attached thereto, axially on to a conveyor belt, subsequently arresting the forward movement of the conveyor belt, displacing a wrapping device, while the conveyor belt and assemblage are stationary, lengthwise along the assemblage in a direction opposite to the feed movement to wrap the uniting band around the assemblage, discharging the assemblage axially by subsequent feed movements, and subsequently bisecting the united assemblages to produce individual cigarettes.
- 15 9. An apparatus for the production of filter tip cigarettes, comprising means for intermittently displacing assemblages of lengths of axially aligned cigarettes and filter tip portions in a lengthwise direction, means for applying a uniting band to each assemblage, positioning means for stopping an assemblage, between intermittent displacements, in register with the band applying means, means for actuating said positioning means to interpose it in the path of displacement of said assemblages and remove the same therefrom, an endless conveyor by which an assemblage of lengths of cigarette rod and filter tips to be united, with uniting bands attached thereto, are fed axially, means for driving the conveyor intermittently, wrapping means reciprocable lengthwise of the conveyor, and mechanism operating the said wrapping means so that its wrapping movement in a direction opposite to the feed movement of the conveyor takes place while the conveyor is stationary and so that its return movement coincides substantially with the forward movement of the conveyor.
- 20 10. In an apparatus of the character described, means for supporting an assemblage of axially aligned cigarettes and filter tip lengths to be united, with one side of said assemblage exposed, an intermittently moving conveyor for feeding a

- uniting band to a supported assemblage, and means for shifting said conveyor toward the assemblage to apply a band on said conveyor to the assemblage.
- 5 11. An apparatus for the production of filter tip cigarettes, comprising means for intermittently displacing assembled lengths of axially aligned cigarettes and filter tip portions in a lengthwise direction, a slotted tube for supporting an assemblage of said lengths, an intermittently movable conveyor for conveying uniting bands to a position beneath said slotted tube, and means for raising said conveyor to apply a uniting band carried thereby to the assemblage 10 supported in said tube.
- 15 12. An apparatus for the production of filter tip cigarettes, comprising means for intermittently displacing assembled lengths of axially aligned cigarettes and filter tip portions in a lengthwise direction, a slotted tube for supporting an assemblage of said lengths, an intermittently movable conveyor for conveying uniting bands to a position beneath said slotted tube, means for raising said conveyor to apply a unit- 20 ing band carried thereby to the assemblage supported in said tube, an endless conveyor by which assembled lengths of cigarettes and filter tips to be united, with uniting bands attached thereto, are fed axially, means for driving the conveyor intermittently, wrapping means reciprocable lengthwise of the conveyor, mechanism operating the said wrapping means so that its wrap- 25 ping movement in a direction opposite to the feed movement of the conveyor takes place while the conveyor is stationary and so that its return movement coincides substantially with the forward movement of the conveyor, and an ex- 30 tension carried by said suction box for supporting the uniting band applied to the assemblage during movement thereof to the endless conveyor.
- feed movement of the conveyor takes place while the conveyor is stationary and so that its return movement coincides substantially with the forward movement of the conveyor.
13. An apparatus for the production of filter tip cigarettes, comprising means for intermittently displacing assembled lengths of axially aligned cigarettes and filter tip portions in a lengthwise direction, a slotted tube for supporting an assemblage of said lengths, an intermittently movable conveyor for conveying uniting bands to a position beneath said slotted tube, a suction box beneath said slotted tube and over which the uniting band conveyor travels, means for raising said suction box to bring a uniting band supported thereon into engagement with the assemblage supported in said tube, an endless conveyor by which assembled lengths of cigarettes and filter tips to be united, with uniting bands attached thereto, are fed axially, means for driving the conveyor intermittently, wrapping means reciprocable lengthwise of the conveyor, mechanism operating the said wrapping means so that its wrapping movement in a direction opposite to the feed movement of the conveyor takes place while the conveyor is stationary and so that its return movement coincides substantially with the forward movement of the conveyor, and an extension carried by said suction box for supporting the uniting band applied to the assemblage during movement thereof to the endless conveyor.

ROWLAND FRANK MAY.
